C. S. WOODS.

ADJUSTABLE BEDSTEAD FOR INVALIDS.
APPLICATION FILED JUNE 17, 1921.

1,417,654.

Patented May 30, 1922.

UNITED STATES PATENT OFFICE.

CHARLES S. WOODS, OF INDIANAPOLIS, INDIANA.

ADJUSTABLE BEDSTEAD FOR INVALIDS.

1,417,654.

Specification of Letters Patent. Patented May 30, 1922.

Application filed June 17, 1921. Serial No. 478,255.

To all whom it may concern:

Be it known that I, CHARLES S. Woods, a citizen of the United States, and a resident of Indianapolis, county of Marion, and State 5 of Indiana, have invented a certain new and useful Adjustable Bedstead for Invalids; and I do hereby declare that the following is a full, clear, and exact description thereof, reference being had to the accompanying 10 drawings, in which like numerals refer to like parts.

This invention relates to invalid and fracture beds and the like, and the chief object of the invention is to provide a simplified 15 mechanism which can be readily associated with a standard bed to transform the same into a fracture or invalid's bed.

Heretofore when there was a fracture case, a complete fracture bed had to be obtained, 20 and after the case was disposed of this type of bed had to be removed or stored away. By means of this invention, the standard bed may be transformed into a fracture bed by merely securing the attachment thereto.

25 The chief feature of the invention consists in providing an auxiliary bed frame, with suitable elevating means which may be detachably connected to the standard bed legs for supporting the said frame, said elevating 30 means including worm and worm gear drives.

Another feature of the invention consists 35 in the guide means associating the bedstead and the elevating means, whereby said elevating means will be maintained in aligned relation and which will also prevent collapsing thereof when the auxiliary bed frame is in the elevated position.

Another feature of the invention consists 40 in providing adjustable elevating means with suitable power means, which permits the former and the latter to be attached with equal facility to beds of varying sizes.

The full nature of the invention will be 45 understood from the accompanying drawings and the following description and claims.

In the drawings, Fig. 1 is a perspective view of a bedstead provided with an auxiliary bed frame and means for elevating the 50 same. Fig. 2 is a top plan view of the elevating means. Fig. 3 is a sectional view taken on line 3—3 of Fig. 2 and in the direction of the arrows to illustrate the worm 55 and worm wheel connection. Fig. 4 is a

sectional view of the rack and gear elevating means and is taken on line 4—4 of Fig. 2.

In the drawings 10 indicates a bed spring supporting a bed mattress 11, and said bed spring is supported by the head and foot 60 portions 12 and 13 respectively, each of which is provided with the usual vertical leg portions 14. Positioned above the mattress 11 is an auxiliary bed frame 15 which is of substantially the same area as the mattress 65 11 and is adapted to rest above the same when in the lowered position.

Heretofore it has been old to provide means for elevating the aforesaid auxiliary bed frame, but said means such as breakable 70 straps, have been cumbersome or crude in comparison to the simplicity of applicant's device. Furthermore, it has been the custom to provide in devices of this character suitable dog and ratchet means for limiting the 75 return movement of the auxiliary bed frame. In the present invention the necessity for ratchet means is eliminated by the use of worm and worm wheel drives associated with each of the elevating pillars. Another 80 improvement is the provision of means for preventing the collapsing of the auxiliary bed frame and elevating means when in the elevated position. Still another improvement embodied in this invention is its 85 applicability to beds of varying sizes.

The means for both elevating and supporting the auxiliary bed frame comprises a pillar or standard 16, which is suitably secured thereto by a bracket, as shown, or 90 otherwise, as desired. The standard or pillar 16 is provided with a plurality of teeth 17 upon one face thereof, thereby forming a rack. The rack upon one face thereof is provided with a longitudinally extending slot 95 18, and said slot or groove is adapted to receive a tongue or key 19 attachably associated with the leg 14. Said attachable tongue provides a tongue and groove connection with the rack and maintains said rack 100 in alignment such that when the four racks at the four corners of the rectangular auxiliary bed frame are elevated, said tongues maintain said racks in alignment, and, therefore, prevent the collapsing of the auxiliary 105 bed frame and serve to maintain the same in a horizontal plane.

The means associated with the rack means includes a bracket 20 which is attachably associated by means of the set screw 21 with 110

the leg 14. The bracket member 20 includes a pair of aligned openings 22 which slidably support the rack 16, see Fig. 4. The bracket 20 also is in the form of a housing and provides bearings for a shaft 23 upon which is suitably secured a pinion gear 24 in mesh with the teeth 17 of the rack 16. Also positioned upon the shaft 23 is a worm wheel 25, and said worm wheel meshes with a worm 26, which worm is keyed or otherwise suitably secured to a shaft which also is rotatably supported in each of the brackets.

Herein three shafts are illustrated, to-wit, the shafts 27, 28 and 29. The shaft 27 is fashioned to receive a crank handle 30. Also positioned upon said shaft is a bearing 31 for rotatably supporting one end of the longitudinally extending shaft 28. Upon the shafts 27 and 28 is a pair of meshing bevel gears 32 suitably secured to said shafts so as to be rotatable therewith and thereby. The other end of the shaft 28 is similarly associated with the shaft 29 and is similarly provided with a pair of bevel gears 132 such that rotational movement of the crank handle 30 causes the shafts 27, 28 and 29 to rotate, thereby rotating each of the worms 26 in the desired direction. Thus, the simultaneous rotation of the worms 26 will cause the simultaneous rotation of each of the worm wheels 25 and the gear wheels 24 so that each of the racks 16 will be elevated or lowered simultaneously with the others.

It will be noted from Fig. 2 that the shafts 27, 28 and 29 are so associated together that they may be moved slidably with respect to their supports, to-wit, the brackets 20 and the bearings 31, thereby providing that the attachments and the shaft will be adjustable to varying sizes of beds.

The invention claimed is:

1. The combination with a standard bedstead, a mattress mounted thereon, and a spring construction for supporting said mattress, of an attachment for converting said bed into an invalid bed comprising an invalid bed frame structure adapted to be supported over said mattress, a plurality of standards secured to said frame structure having ratchet teeth thereon, pinions

engaging said teeth, a plurality of shafts for driving said pinions whereby said frame standard may be elevated or lowered with respect to said bedstead, and means for detachably securing said shafts and standards to said bedstead so as to be removable therefrom.

2. The combination with a standard bedstead, a mattress mounted thereon, and a spring construction for supporting said mattress, of an attachment for converting said bed into an invalid bed comprising an invalid bed frame structure adapted to be supported over said mattress, a plurality of standards secured to said frame structure having ratchet teeth thereon, pinions for engaging said teeth, a longitudinally adjustable shaft for driving said pinions whereby said frame standards may be elevated or lowered with respect to said bedstead, and means for detachably securing said shafts and standards to said bedstead so as to be removable therefrom and adjustable to the varying sizes thereof.

3. The combination with a standard bedstead, of an adjustable and detachable invalid bed frame adapted to be mounted thereon, including a frame structure, a plurality of standards for supporting said structure having ratchet teeth thereon, a housing detachably mounted on said bedstead through which said standards are arranged to extend, pinions mounted in said housing in position to engage the ratchet teeth of said standards, shafts for supporting said pinions, worm gears mounted on said shafts, transverse shafts extending between said housings having worms thereon in position to engage said worm gears, means for turning said shaft so as to elevate and lower said bed structure, and a longitudinally adjustable shaft operatively connected with said transverse shafts mid-way between the ends thereof, whereby said shafts may be simultaneously operated for adjusting said bed structure.

In witness whereof, I have hereunto affixed my signature.

CHARLES S. WOODS.
